UNITED STATES PATENT OFFICE

ANTON J. HAUG, OF NASHUA, NEW HAMPSHIRE

CENTRIFUGAL PAPERSTOCK SCREEN

Application filed June 10, 1929. Serial No. 369,618.

This invention relates to apparatus for and process of removing undesirable substances from paperstock and similar material, and is particularly intended for use to accomplish the final screening operation ahead of the papermachine, where it is necessary that all particles of foreign matter be withdrawn from the stock and that all fiber clusters, which may have formed during previous operations in the preparation of the paperstock, be disintegrated or removed.

The machines now used for the final screening operation, known as papermachine screens, are not particularly efficient or capable of handling very large volumes of stock; and, while they do succeed in freeing the stock of most of the fiber mats, they lack means to remove fine particles of sand, cinders, etc., which are of greater specific gravity than the stock fibers themselves, as well as minute lighter impurities which float.

Special dirt separators are now coming into use in the industry, such separators being designed to assist the operation of the papermachine screens. These separators are low-capacity apparatus, however, and since a moderate production of paperstock would require a large number of separating machines, the use of such separators in conjunction with the present papermachine screens would tend to increase costs and congestion in even moderate-size mills.

The principal object of the present invention is therefore the production of a machine which will deliver economically a relatively large volume of well-screened and cleansed stock, combining the two functions of the papermachine screen and the dirt separator in a single, simply-constructed apparatus.

In carrying out the objects of the invention, I have utilized some of the broad principles covered in my Patents #1,533,410 dated April 14, 1925, #1,551,953, dated Sept. 1, 1925 and #1,755,162, dated April 15, 1930 and in my co-pending applications Serial #331,178 filed Jan. 9, 1929 and 366,241 filed May 27, 1929.

Referring now to the accompanying drawings,

Figure 1 shows a vertical sectional eleva-

tion of a preferred form of machine embodying the principal elements of the invention,

Fig. 2 is a longitudinal elevation partly in section illustrating the manner in which the chief features of the invention may be applied to a machine of horizontal construction, the internal equipment of this latter machine being identical with that of machines disclosed in my prior patents hereinabove referred to,

Fig. 3 is an end view, partly in section, taken on lines *a*—*a* of Fig. 2, and showing particularly the outlet for heavy impurities, and

Fig. 4 is a detail view in section of the device for removing heavy impurities.

In the drawings, 1 (Fig. 1) denotes a preferably, though not necessarily, conical casing which, with cover 2, forms a stationary container wherein the chief operating part of the invention, comprising a cylindrical basket composed of an imperforate dish-shaped bottom 3 provided with a centrally-disposed tubular extension forming hollow shaft 4, a head 5 and foraminous walls 6, is positioned to revolve. The container is supported on legs 7.

Shaft 4 is carried in two sets of ball bearings 8 and 8a, one race 9 of each of said bearings being held in casings 10 attached to lugs 11 cast on legs 7, and the other race 9a of each bearing fast to turn with the shaft.

12 denotes an electric motor connected to shaft 4 by a worm 12a attached to the motor shaft and a worm gear 12b fastened to shaft 4, providing means to drive said shaft at any desired speed.

Paperstock in suitably dilute condition is introduced into the machine through stationary inlet 13 which enters the container centrally thereof and discharges the incoming stock through mouth 14 against a spreader 15 which distributes the stock along the inner circumference of the basket, the relatively fine portion of the solids, including good stock fibers, fine dirt, etc. being driven by centrifugal force produced by the rapid revolution of the basket through the perforations in the circumference of the basket, while the larger material comprising larger impurities and

clusters of undisintegrated material, known as tailings, remain in the interior of the basket until discharged as hereinafter explained—the principle being as disclosed in 5 my prior patents above referred to.

Water may be admitted to circular chamber 16 in the interior of the basket through pipe 17 to thin and wash the tailings, which are moved toward tailings outlet 18 by the 10 revolution of the basket in connection with the inclined bars 19, which are held suitably close to the perforated circumference of the basket by means of arms 20 attached to spreader 15 and arms 20a fastened to the 15 walls of water-chamber 16.

When the tailings reach the lower end of the basket, they are scraped out therefrom by adjustable scoop 21, adjustment for which is provided by the combination of bar 22; 20 worm 23, worm gear 24 and handwheel 25— all of which is similar to the device for a like purpose shown in my copending application Serial 327,390 issued as Patent 1,755,162 dated April 15, 1930. After being scraped from 25 the basket, the tailings are discharged from the machine through pipe 26 extending through hollow shaft 4.

The relatively fine stock which has passed through the perforations of the basket is given 30 a rapid whirling motion, due to contact with the rapidly revolving basket, the relatively heavy impurities in said stock being thrown to the circumference of the container and finally collecting in that section thereof which 35 has the largest diameter, which, in the case of the present machine, is the bottom of the container, whence it may be automatically withdrawn through outlet 27 (see particularly Figs. 1 and 4) attached to or cast on 40 cylindrical casing 28 in which a valve body 29 keyed to shaft 30 is adapted to revolve, motion being imparted to said shaft by worm 31, worm gear 32 and electric motor 33. The valve is provided with a pocket 34 which, as 45 the valve rotates, periodically registers with outlet 35 of the container and withdraws a quantity of heavy impurities which have collected near said outlet, said impurities being then carried by said pocket until it reaches 50 mouth 27 where the impurities are discharged out of the machine. The outer circumference of the valve is furnished with numerous recesses to catch dirt which might otherwise become wedged in between the 55 valve and casing 28, and cramp the valve in its rotation.

The cleansed stock, thus freed of both coarse material and fine, relatively heavy impurities, rises to the top of the container, 60 where it flows through approximately circular outlet 36, which is formed by the inner edges of shutter-fingers 37, the latter being unitedly-movable inward or outward to contract or enlarge said outlet by adjustment of 65 handwheel 38, similar to the arrangement

shown in my co-pending application Serial 366,241. The stock, after passing through outlet 36, enters trough 39 wherein it is forced under an adjustable lip 40, the upper edge of which is so positioned as to be adapted to 70 skim the light, floating impurities from the surface of the stock, said impurities being discharged through pipe 41 and the clean stock flowing out of the machine through mouth 42.

It is desired to be understood that although I have described one specific embodiment of my invention, other constructions may be employed to carry out the novel features of 75 said invention. For instance, a horizontal machine may be constructed as shown in Fig. 2; or the circumference of the revoluble basket may be furnished with slots instead of perforations as disclosed herein, or it may be composed of wire cloth; or the said basket 80 may be stationary, instead of revoluble, and the stock may be impelled through the openings thereof by a rotor inside said basket, and the casing may be revolved either independently of, or in connection with, rotation 85 of the basket, all of which is subordinate to the main novel principle of combining the functions of a screen and a dirt separator in 90 a single machine of the centrifugal type.

Having thus described my invention, what 95 I desire to claim as new is:

1. In a separating machine for paperstock and similar material, the combination with a container, of means to introduce liquid stock thereinto, means to remove the relatively coarse material from said stock, means to separate the relatively heavy impurities from the fine, or screened, stock, and means to withdraw the relatively light, screened fine 100 stock separately from the container.

2. In a separating machine for paperstock and similar material, the combination with a container, of means to introduce liquid stock thereinto, means to remove the relatively coarse material from said stock, means to separate the relatively heavy impurities from the fine, or screened, stock, means to withdraw the relatively light, screened, fine 110 stock separately from the container, and separate, automatic means to withdraw the relatively heavy impurities from said container.

3. In a screening machine for paperstock and similar material, the combination with a container, of means to introduce liquid stock thereinto, a rotating screen drum in 120 said container, means to revolve said drum rapidly to separate both the relatively coarse material and the relatively heavy impurities from said stock, and means to withdraw the relatively light, screened fine stock separately from the container.

4. In a screening machine for paperstock and similar material, the combination with a conical container, of means to introduce liquid stock thereinto, means to separate the 125

5 relatively coarse material from said stock, a special agency to move said separated coarse material toward the outlet therefor, means to separate the relatively heavy impurities from the stock, and means to withdraw the relatively light, screened fine stock separately from the container.

10 5. In a separating machine for paperstock and similar material, the combination with a container, of means to introduce liquid stock thereinto, means to cause relative motion between said stock and said container to remove the relatively coarse material from said stock and to separate the relatively heavy impurities from the fine, or screened, stock, and means to withdraw the relatively light, screened fine stock separately from the container.

20 6. In a separating machine for paperstock and similar material, the combination with a container, of a rotor therein, means to supply liquid stock to the interior of said rotor, means to revolve said rotor rapidly to force the relatively fine stock out of said rotor and to separate impurities from the stock surrounding said rotor, and means to withdraw the separated coarse stock, the impurities and the relatively light, screened fine stock separately from the container.

25 30 7. In a separating machine for paperstock and similar material, the combination with a container, of means to introduce liquid stock thereinto, a separating agency adapted to operate in said stock to separate the relatively coarse material and the impurities therefrom, and means adjustable during the operation of the machine to control the amount of stock subjected to the impurities-separating action at any one time, at the discharge of the relatively fine stock.

35 40 8. In a screening machine for paperstock and similar material, the combination with a container, of means to introduce liquid stock thereinto, means to subject all the stock entering said container to two grading operations, by one of which operations said solids are graded according to weight and by the other of which operations said solids are graded according to size, and means to withdraw the acceptable stock separately from the container.

45 50 55 60 9. In a screening machine for paperstock and similar material, the combination with a container, of a separating chamber therein, means to introduce liquid stock into said chamber, means to remove relatively coarse material from the stock, means to separate the relatively fine, heavy impurities from the stock, means to retard the escape of the stock undergoing treatment from the separating chamber to permit a prolonged separating operation, means to withdraw the relatively coarse material, the relatively fine, heavy impurities and the relatively light, fine

screened stock separately from the container.

10 15 20 25 30 35 40 45 50 55 60 65 70 75 80 85 90 95 100 105 110 115 120 125 130

10. In a screening machine for paperstock and similar material, the combination with a container, of a separating chamber therein, means to introduce liquid stock into said chamber, means to remove relatively coarse material from the stock, means to separate the relatively fine, heavy impurities from the stock, means to retard the escape of the stock undergoing treatment from the separating chamber to permit a prolonged separating operation, means to withdraw the relatively coarse material, the relatively fine, heavy impurities and the relatively light, fine screened stock separately and continuously from the container.

In testimony whereof, I have signed my name to this specification.

ANTON J. HAUG.
